UNITED STATES PATENT OFFICE

135,345

DESIGN FOR A FEEDBOX FOR LATHES

Richard K. Le Blond, Cincinnati, Ohio

Application October 15, 1942, Serial No. 108,534

Term of patent 14 years

To all whom it may concern:

Be it known that I, Richard K. Le Blond, a citizen of the United States and a resident of Cincinnati, county of Hamilton, and State of Ohio, have invented a new, original, and ornamental Design for a Feed Box for Lathes, of which the following is a specification, reference being had to the accompanying drawings, forming part thereof.

Figure I is a front elevational view of a feed box for lathes embodying my new design.

Figure II is a right hand end elevation of the feed box shown in Figure I.

Figure III is a left hand end elevation of the feed box shown in Figure I.

Figure IV is a plan view of the feed box shown in Figure I.

I claim:

The ornamental design for a feed box for lathes, substantially as shown.

RICHARD K. LE BLOND.
